UNITED STATES PATENT OFFICE.

JAMES J. HENNESSY, OF NEW YORK, N. Y.

AUTOMATIC JOURNAL-LUBRICATOR.

1,378,452.

Specification of Letters Patent. Patented May 17, 1921.

Application filed August 15, 1918. Serial No. 250,045.

To all whom it may concern:

Be it known that I, JAMES J. HENNESSY, a citizen of the United States, residing at New York city, New York, have invented 5 a certain new and useful Improvement in Automatic Journal - Lubricators, of which the following is a full, clear, and exact description, such as will enable others skilled in the art to which it appertains to make 10 and use the same, reference being had to the accompanying drawings, forming part of this specification.

My invention relates generally to lubricating devices and more specifically to a rail- 15 way car journal lubricator of the type disclosed in Patents Nos. 1,265,198 and 1,265,199 issued to me May 7, 1918.

The principal objects of my invention are, 20 to generally improve upon and simplify the construction of the lubricating devices disclosed in the aforesaid patents, and to provide a relatively simple lubricating device which is wholly automatic in its operation, positive in action, and effective to a high 25 degree in performing the functions for which it is intended.

In Patent No. 1,265,199 above referred to, 30 the piston of the pump utilized for effecting a circulation of liquid lubricant is operated by inertia resulting from the longitudinal movement of the journal within the journal box, and as distinguished from this arrangement, my present construction contemplates a structure wherein the pumping mechanism 35 is operated by direct contact with the journal or a part carried thereby, it being understood that while in operation car axles have, in addition to their rotary movement, a slight longitudinal movement, and con- 40 sequently the journals on the ends of said axles move backward and forward longitudinally through the journal boxes, the latter being fixed to the car trucks. This longitudinal movement of the car axles is due 45 to a number of causes, principally to slight vertical and transverse variations in the track rails and I propose to use this slight lengthwise movement of the axles to effect the actuation of a pump or pumping means,

50 and thereby bring about a circulation of lubricating oil from the lubricant container within the journal box to the container in which the waste is positioned, and which latter, it will be understood, makes direct 55 contact with the lower half of the journal.

With the foregoing and other objects in

view, my invention consists in certain novel features of construction of parts, hereinafter more fully described and claimed, and illustrated in the accompanying drawings, in 60 which—

Figure 1 is a vertical section taken lengthwise through the center of an improved journal lubricating device of my improved construction.

Fig. 2 is a transverse section taken approximately on the line 2—2 of Fig. 1.

Fig. 3 is a transverse section taken approximately on the line 3—3 of Fig. 1.

Fig. 4 is an enlarged detail section taken 70 approximately on the line 4—4 of Fig. 1.

Fig. 5 is a vertical section of a journal box, and showing a modified form of my improved automatic lubricator.

Fig. 6 is a vertical section taken approximately on the line 6—6 of Fig. 5.

Fig. 7 is a vertical section taken through the center of a journal box and showing a further modified form of automatic lubri- 80 cator.

Fig. 8 is a vertical section taken approximately on the line 8—8 of Fig. 7.

Referring by numerals to the accompanying drawings, and particularly the form of lubricator illustrated in Figs. 1 to 4 inclusive which is designed especially for locomotive trucks and driver journals, 10 designates a liquid lubricant container or receptacle which is rigidly fixed in any suitable manner to a part of the locomotive frame. 90 This receptacle comprises a bottom, side walls, and end walls, the upper portions of the latter being cut away to form semi-circular openings which receive the journal A. Positioned within this receptacle and yieldingly supported upon a compression spring 11 is a specially formed casting which carries the operating parts of the pump utilized for circulating the liquid lubricant and said casting comprises a horizontally 100 disposed bottom plate 12, and upwardly presented concave plate 13, and end walls 14, the upper portions of the latter being provided with curved seats 15 which fit snugly against the periphery of the journal.

Inasmuch as the spring exerts considerable upward pressure on the casting just described, the joints between the seats 15 and the journal are practically oil-tight.

The concave plate 12 is positioned in a 110 plane a short distance below the periphery of the journal A when the parts are prop-

- erly assembled for use, and the space 16 between plate 12 and journal and between the end walls 14 serves as a waste chamber, that is, it contains a body of waste or like fibrous material which makes direct contact with the surface of the journal. To retain the waste in this chamber, upwardly projecting ribs or prongs 17 are formed integral with the plate 12.
- 10 Formed integral with plate 12 and depending therefrom is a longitudinally disposed cylinder 18 and mounted for reciprocating movement in the chamber 19 therein is a double-ended piston 20 through the center of which is formed a vertically disposed aperture 21. Formed through the side walls of the cylinder 18 at points between its center and ends are oil inlet openings 22. Formed through the center of plate 12 is a longitudinally disposed bore 23, and formed in said plate at a point intermediate its ends and connecting the central portions of this bore 23 and chamber 19 is a vertically disposed aperture 24.
- 15 25 Mounted for reciprocatory movement in bore 23 is a plunger rod 25, the rear portion of which is reduced in diameter, as designated by 26, and the end of this reduced portion bears in a cylindrical plug 27, the latter being screw-seated in the rear end of bore 23. Located on the reduced portion 26 of this plunger rod is a compression spring 28, one end of which bears against the shoulder at the forward end of the reduced portion 26 and the other end bearing against plug 27.
- 20 Formed in the central portion of rod 25 is a vertically disposed aperture 29 in which is loosely mounted the upper end of a lever 30, the lower end thereof occupying aperture 21 in piston 20. This lever is fulcrumed on a pin 31, the same being seated in plate 12.
- 25 The outer end of plunger rod 25 projects slightly beyond the end of plate 12 and said outer end carries a loosely mounted ball 32, the outer portion of the latter projecting beyond the outer face of receptacle 10 or in such position as to be engaged by the hub B of the wheel carried upon journal A.
- 30 35 Formed in plate 12 and communicating with the ends of chamber 19 are vertically disposed openings 23 in the lower portions of which are formed suitable seats upon which normally rest ball valves 34.
- 40 45 50 55 60 65 70 75 80 85 90 95 100 105 110 115 120 125 130 Formed in both directions from each opening 33 through the curved plate 12 are transversely disposed ducts or passageways 35, the outer ends thereof communicating with the waste chamber 16 at points near the sides thereof.
- In the construction of the automatic lubricator just described, it will be understood that receptacle 10 occupies a relatively fixed position and that journal A carrying wheel B in addition to its rotary movement has a

slight lengthwise or longitudinal movement, and it is this latter movement that is depended upon to automatically operate the pump for circulating liquid lubricant from the chamber within container 10 to the waste filled chamber 16. During the slight longitudinal movement in one direction, the hub of wheel B will bear against ball 32 seated in the outer end of plunger rod 25 thereby forcing the latter inward against the resistance offered by spring 28 and as parts A and B move in the opposite direction, said spring 21 will act to return the plunger rod to its outer limit of movement. Thus, while the journal and wheel are in operation, plunger rod 25 will be continuously reciprocated, and through the medium of lever 29, plunger 20 will be reciprocated in chamber 19 with the result that liquid lubricant in the ends of said chamber will be forced upward past ball valves 34 into openings 33 and from thence upwardly through ducts 35.

The liquid lubricant thus forced upwardly will discharge from the upper ends of the ducts directly into the body of waste container within the space or chamber 16 and by said waste, the liquid lubricant will be delivered directly to the surface of journal A, thereby effectually lubricating the latter.

It will be understood that it is necessary to maintain a supply of liquid lubricant within container 10 and as piston 20 is moved alternately in opposite directions, the pairs of apertures 22 are uncovered, thereby permitting the liquid lubricant to pass from the chamber within container 10 into the end portions of chamber 19.

Referring now to the modified construction illustrated in Figs. 5 and 6, 36 designates a journal box of the standard M. C. B. type, 37 an axle, and 38 the journal on the end of said axle and which occupies the journal box. Arranged within the lower portion of the journal box and inclosing the lower portion of the journal is a receptacle 39, the same being supported upon compression springs 40 and the inner end of the wall of this receptacle fits snugly against the axle 37 at a point just beyond the inner end of journal 38.

Formed on the inner faces of the sides of this receptacle are longitudinally disposed ball races 41 in which are positioned balls 42 and supported thereby is a concave plate 43, the same being positioned immediately beneath journal 38 with its ends bearing against the shoulders at the ends of said journal. This concave plate is positioned a short distance below the periphery of the journal and the space 44 between said plate and journal is occupied by a body of waste or like fibrous material which contacts directly with the surface of the journal. This body of waste is retained in

position by means of ribs or prongs 45 which project upwardly and inwardly from plate 43.

Formed integral with the underside of plate 43 is a longitudinally disposed housing 46 in which is formed a chamber 47 and mounted for reciprocatory movement in said chamber is a double-ended piston 48. Formed in the underside of the central portion 10 of this piston is a transversely disposed notch 49, the same being occupied by a transversely disposed flange or web 50 the latter being formed integral with the bottom of receptacle 39. Formed through 15 the side walls of housing 46 and communicating with the piston chamber 47 are oil inlet apertures 51. Formed through plate 43 and communicating with the ends of piston chamber 47 are openings 52, the lower 20 portions of which are provided with seats upon which normally rest ball valves 53.

In this form of automatic lubricator, it will be understood that receptacle 39 occupies a fixed or stationary position relative 25 to the axle and journal and that concave plate 43 which carries the body of waste moves longitudinally with the journal 38 and consequently moves backward and forward within receptacle 39. Piston 48 is 30 held practically stationary by engagement with web or flange 50, and as the waste carrying plate 43 moves backward and forward the movement of housing 46 relative to piston 48 will produce a pumping action 35 with the result that liquid lubricant will enter chamber 47 through apertures 51 and this lubricant will be forced upward past ball valves 53 and will discharge from openings 52 directly onto the body of waste positioned in the space 44 with the result that 40 the surface of the journal 38 will be continuously lubricated while said journal is in motion.

In the modified construction illustrated in 45 Figs. 7 and 8, 54 designates a journal box and 55 the journal operating therein. Formed integral with the box at a point above the bottom thereof is a concave plate 56 which occupies a position immediately 50 beneath the journal 55 and serves to hold a body 57 of waste, the same contacting directly with the surface of the journal. Formed integral with the bottom of box 54 and preferably near the center thereof is a 55 vertically disposed cylinder 58 in which is mounted for reciprocatory movement a piston 59. Formed through the lower portion of the cylinder 58 is one or more apertures 60, the same serving to establish 60 communication between the chamber in the bottom of the box and the lower portion of the piston chamber in cylinder 58.

Leading outwardly and upwardly from the lower portion of cylinder 58 and preferably formed integral with the box 54 is

a tubular housing 61 within which at a suitable point is located a ball valve 62. The upper end of this tubular housing is preferably closed by a plug or cap 63, and formed through the wall of the housing so as to establish communication between the chamber within said housing and the space occupied by the waste is an aperture 64. Formed in the outer end wall of box 54 and preferably in alignment with the axis of 75 journal 55 is a horizontally disposed housing 65 in which is loosely mounted a short plunger rod 66, the inner end thereof normally bearing directly against the outer face of journal 55. Arranged within the housing 80 65 behind this plunger rod is a compression spring 67.

Fulcrumed on a suitable bracket on the outer end of plate 56 is a bell crank lever 68, the end of the vertical arm of which is 85 operatively associated with plunger rod 66 and the end of the horizontal leg of this lever is operatively associated with piston 59.

In this construction it will be understood 90 that the journal 55 has a slight longitudinal movement relative to journal box 54, and as this longitudinal movement takes place, plunger rod 66 will be forced outward as a result of pressure from the longitudinally moving journal 55 and when the journal 95 moves in the opposite direction, spring 67 will act to correspondingly move plunger 66. This reciprocatory movement of plunger rod will be transmitted to bell crank lever 68 with the result that piston 59 will be reciprocated vertically within housing 68 and liquid lubricant entering the lower portion 100 of this piston chamber through aperture 60 will be forced outwardly and upwardly through tubular housing 61, past ball check 105 62 and this liquid lubricant will finally discharge through aperture 64 into the space above plate 56 which is occupied by the body of waste.

A lubricating device of my improved construction is comparatively simple, can be readily combined with the prevailing types of journal boxes, is wholly automatic in operation, and provides efficient means for effecting a circulation of liquid lubricant to 110 the waste or like material which contacts directly with the journal of the axle, thus insuring constant lubrication to that portion of the journal which engages the brass or journal bearing.

It will be readily understood that minor 115 changes in the size, form and construction of the various parts of my improved lubricating device may be made and substituted for those herein shown and described, without departing from the spirit of my invention, the scope of which is set forth in the appended claims.

I claim:

1. The combination with a journal box, 130

- of a container provided with a liquid lubricant compartment and a separate waste compartment, which container is yieldingly supported beneath an axle journal, a pump 5 within said container for delivering liquid lubricant from the liquid lubricant compartment to the waste compartment, and means for actuating said pump, the operation of which pump actuating means is dependent 10 upon the longitudinal movement of the journal with respect to the container.
2. The combination with a journal box, of a container provided with a liquid lubricant compartment and a separate waste compartment, which container is yieldingly supported beneath an axle journal, a pump 15 within said container for delivering liquid lubricant from the liquid lubricant compartment to the waste compartment, and means including a spring-pressed member which is directly engaged by the journal during its longitudinal movement for operating said pump.
3. The combination with a journal box, of yieldingly supported means for retaining a body of waste in direct contact with the journal operating in said box, a pump associated with said yieldingly supported means for delivering liquid lubricant into the waste 25 holding means, and means for actuating said pump, the operation of which pump actuating means is dependent upon the longitudinal movement of the journal with respect to the journal box.
4. The combination with a journal box, of yieldingly supported means for retaining a body of waste in direct contact with the journal operating in said box, a pump associated with said yieldingly supported 30 means for delivering liquid lubricant into the waste holding means, a spring-pressed member adapted to be directly engaged by the journal during its longitudinal movement relative to the journal box, and oper-

ating connections between said spring- 45 pressed member and pump.

5. The combination with a journal box, of a liquid lubricant container yieldingly supported within the box beneath the journal therein, a waste container mounted for reciprocating movement within the liquid lubricant container, a pump adapted to effect a circulation of liquid lubricant from said liquid lubricant container into the waste container, and means for actuating said 50 pump, the operation of which pump actuating means is dependent upon the longitudinal movement of the journal with respect to the journal box.

6. The combination with a journal box, of a pump yieldingly supported in the journal box and adapted when operated to effect a circulation of liquid lubricant within said box, a spring-pressed member adapted to be directly engaged and actuated by the lengthwise movement of the journal within said box, and operating connections between said spring-pressed member and pump.

7. The combination with a journal box, of a liquid container positioned beneath the journal in the box, and a waste container arranged for reciprocatory movement within said liquid container.

8. The combination with a journal box, of a liquid container positioned beneath the journal in the box, a waste container arranged for reciprocatory movement within said liquid container, and a pump associated with said containers for effecting a circulation of liquid lubricant from the liquid lubricant container to the waste container.

In testimony whereof I hereunto affix my signature this 9th day of August, 1918.

JAMES J. HENNESSY.
